INVENTOR:
ROYAL F. STRICKLAND,
BY *Almon B. Davis*,
HIS ATTORNEY.

UNITED STATES PATENT OFFICE.

ROYAL F. STRICKLAND, OF CLEVELAND, OHIO, ASSIGNOR TO GENERAL ELECTRIC COMPANY, A CORPORATION OF NEW YORK.

MOUNTING FOR INCANDESCENT LAMPS.

1,373,920.

Specification of Letters Patent.

Patented Apr. 5, 1921.

Application filed March 6, 1917. Serial No. 152,774.

To all whom it may concern:

Be it known that I, ROYAL F. STRICKLAND, a citizen of the United States, residing at Cleveland, in the county of Cuyahoga, State 5 of Ohio, have invented certain new and useful Improvements in Mountings for Incandescent Lamps, of which the following is a specification.

My invention relates to projection apparatus and especially to an incandescent lamp 10 and mounting for use in such apparatus.

My invention is particularly useful in moving picture projection apparatus employing an incandescent filament lamp of 15 the monoplane type. In order to secure the highest efficiency in operation it is necessary that the plane of the monoplane filament be disposed at right angles to the optical axis of the apparatus and in prior devices 20 the lamp mountings have the disadvantage that the lamp filament is often improperly aligned with reference to the optical axis due to the inaccuracies of the lamp base and receptacle, and especially is this true in the 25 screw base and socket type of lamp mounting. Even when the greatest care is exercised in positioning and alining the socket or receptacle upon inserting the lamp in the receptacle and screwing it home it often 30 occurs that the plane of the filament is inclined to the optical axis of the apparatus. By my invention I avoid this difficulty and insure that the monoplane filament is at all 35 times properly aligned with reference to the moving picture projection apparatus. I accomplish this by means of a particular kind of base and mounting for the base whereby it is impossible to insert the lamp in any other than the correct position with reference 40 to the axis. More particularly I provide on the lamp or lamp base a centering or alining means whose position is predetermined in such a manner with reference to the filament plane and to the lamp support 45 that by the mere act of inserting the lamp in the receptacle the monoplane filament is thereby accurately positioned and aligned to obtain the maximum efficiency. According to the preferred arrangement 50 the alining means comprises the leading-in conductors themselves which project through and beyond the lamp base and are adapted to be received by clamp sockets, the arrangement being such that the lamp is prop-

erly alined upon the insertion of the lead- 55 ing-in wires into the sockets and the clamping thereof securely in position. This arrangement has the further advantage in addition to its alining properties of affording a large contact area between the leading-in 60 conductors and the socket, this being especially desirable in the parallel connected filament type of lamp which consumes large amperage.

For a better understanding of my invention 65 reference may be had to the drawings accompanying this application, Figure 1 of which shows a side view of the lamp and lamp mounting. Fig. 2 is a sectional view thereof. Fig. 3 is a plan view of the lamp 70 mounting and Fig. 4 is a conventional illustration of the lamp and lamp mounting in use with a moving picture projection apparatus.

Referring to the drawings, a lamp 1 is 75 illustrated containing a proposed parallel connected multiple filament of the monoplane type, this filament 2 being mounted therein on suitable supports 3. These supports 3 are electrically connected with the 80 outside supports and conductors 4, both these supports 3 and 4 being of large enough cross-section to carry a large current which amounts in some cases to 80 amperes. These external supports and conductors 4 are 85 adapted to be received by lamp mounting comprising an insulating base 5 and insulating standard 6, this mounting being adapted to be inserted and fixed into the lamp housing 7 of a moving picture projection apparatus, the apparatus comprising a film 8 and an objective 9, and screen 10. The standard 6 of the lamp mounting has fixed to the opposite sides thereof the conducting plates 11, the attachment being made in any 90 convenient manner as for instance by the screw bolts whose heads are countersunk in the insulating standard 6, as illustrated in dotted lines. These plates 11 have attached thereto the screws 12 which receive two 95 thumb clamping nuts, as illustrated, for clamping the conductors 4 between the plates 11 and the plates 13. These plates 11 and 13 conveniently have vertical grooves 100 therein which face each other and receive the conductors 4 and the screws 12 have apertures registering with these grooves for permitting the conductors to pass there-

through. The conducting plates 11 on their free ends carry, as illustrated, suitable terminals for connection with the supply circuit. In the operation of applicant's device 5 the lamp mounting is located in the lamp housing 7 or is adapted to be easily mounted therein with the lamp 1. When a lamp burns out all the operator has to do is to insert a new lamp in a receptacle vacated by 10 the burned out lamp which is easily accomplished by manipulation of the thumb nuts on the screws 12, the leading-in wires or supports 4 insuring that the plane of the monoplane filament 2 is at right angles to the 15 axis of the projection apparatus. Moreover, the difficulties encountered in prior devices due to poor contact between the lamp base and the socket usually due to soldering troubles are entirely eliminated, as a perfect 20 contact of sufficient area is obtained between the conductors 4 and the clamping plates 11 and 13 to avoid undue heating of the lamp base. It will be obvious that the height of the filament tube above the base 5 may be 25 accurately fixed by causing the conductors 4 to contact with said base as shown in Fig. 2.

What I claim as new and desire to secure by Letters Patent of the United States, is:

1. In an illuminating arrangement for 30 projection apparatus the combination of an incandescent lamp having a monoplane filament and a lamp mounting, with leading-in conductors projecting through the lamp base and serving as supports therefor adapted to 35 be received by sockets in the lamp mounting whereby the lamp may be properly aligned with reference to the optical axis of the

projection apparatus merely by the insertion of the lamp leads in the socket.

2. In an illuminating arrangement for projection apparatus the combination of an incandescent lamp having a monoplane filament and a lamp mounting, with leading-in conductors projecting through the lamp base and serving as supports therefor adapted to 45 be received by sockets in the lamp mounting whereby the lamp may be properly aligned with reference to the optical axis of the projection apparatus merely by the insertion of the lamp leads in the socket, said sockets 50 comprising clamping plates and a screw passing through said plates and apertured to receive one of said conductors and a nut engaging said screw and adapted to clamp said plates against said conductors. 55

3. In an illuminating arrangement for projection apparatus the combination of an incandescent lamp having a filament designed so that the light rays emanating therefrom will be at a maximum in a single 60 direction, said lamp having leading-in conductors definitely disposed with reference to said filament projecting through the base thereof and serving as supports therefor and a lamp mounting comprising holding 65 means for receiving the ends of said conductors whereby a lamp may be properly aligned with reference to the aforesaid direction by the insertion of the said conductors in the said holding means.

In witness whereof, I have hereunto set my hand this 3rd day of March, 1917.

ROYAL F. STRICKLAND.
